UNITED STATES PATENT OFFICE

LA RUE B. CHEVALIER, OF IOLA, KANSAS

POLISH ROD HANGER

Application filed June 10, 1929. Serial No. 369,633.

My invention relates to pumping apparatus and more particularly to hangers for connecting one end of a walking beam in a drilling rig with a rod operating in an oil well, for example a polish rod supporting sucker rods in the well and operating in a stuffing box, the principal objects of the invention being to maintain the rod in as nearly a straight line as possible for effecting a straight pull thereon, and to reduce the amount of friction between the rod and the box and thereby save wear and damage to the same and minimize power required for operating the apparatus.

In ordinary practice, a walking beam having a hanger at one end for pivotally supporting the rod is supported at its center on a pivoted bearing, and up and down motion imparted by a crank shaft connected to the other end of the beam for reciprocating the rod causes the hanger to describe an arc on each strike, thus moving the pivoted end of the rod laterally. The greatest distance between the cord of the arc and the arc represents the amount of lateral motion imparted to the portion of the polish rod that projects from the stuffing box.

The lateral motion is objectionable as the polish rod is confined to perpendicular motion within the stuffing box and below the same, so that the out of line movement resulting from the lateral movement of the end of the beam causes the rod to bear against the stuffing box, thus tending to wear the box and the rod, and increasing the amount of power required for operating the apparatus.

Further objects of my invention therefore are to reduce the lateral displacement of a polish rod when reciprocated by a walking beam, and to impart as nearly perpendicular motion to the polish rod as possible.

In accomplishing these and other objects of the invention, I have provided improved details of structure, the preferred forms of which are illustrated in the accompanying drawings, wherein:

Fig. 1 is a perspective view of a portion 50 of pumping apparatus showing my im-

proved hanger mounted on the walking beam and connected with the polish rod.

Fig. 2 is an enlarged longitudinal vertical section of the rod-supporting end of the walking beam and of my device, in horizontal position, the positions of the beam end at extremes of upward and downward movement being shown in dotted lines.

Fig. 3 is a front end elevation of the walking beam and hanger and upper ends of hanger rods.

Fig. 4 is a vertical transverse section of one arm of my improved hanger illustrating the upper and lower hinge pin openings.

Fig. 5 is a perspective view of the lower hinge pin member to which the hanger rods are attached.

Referring in detail to the drawings:

1 designates the supporting structure of oil well equipment, 2 well casing, 3 tubing, and 4 a stuffing box in which a polish rod 5 is slidably mounted. A Samson post 6 comprising a part of the structure supports a trunnion 7 mounted transversely at the midpoint of a walking beam 8 adapted to rock or swing on the post and operated by a crank 9 connected to the beam by a pitman 10 and to a shaft 11 of a band wheel 12 supported by the structure and operated by a prime mover not shown, through a belt 13.

The polish rod is ordinarily pivotally connected to the outer end 14 of the beam for reciprocation in the tubing to operate pumping apparatus therein.

A carrier 15 is fixed to the polish rod, and hanger rods 16 are adapted to connect the carrier with the beam for enabling the beam to support and lift the rod.

My invention includes a hanger generally designated 17 including a hanger head 18 mounted on the end of the beam and hanger arms 19 pivotally mounted on the hanger head and connected with the hanger rods, as presently described.

The head 18 includes laterally spaced plates 20 secured to opposite sides of the end portion of the beam and having depending wing-like portions 21 projecting downwardly from the beam and at right-angles to the axis thereof.

The hanger head may be secured to the beam by a clamp 22 including a U-bolt-like strap 23 and a bar member 24 screwthreadedly engaged with the ends of the bolt and engaging the head.

5 Fixed to the head plates and extending oppositely therefrom, preferably in a plane including the beam trunnion 7 and in longitudinally spaced relation with the trunnion 10 as later described, are lateral studs or trunnions 25 comprising hinge pin supports for the arms 19 which have openings 26 for mounting the same on the pins.

15 The arms project an appreciable distance below the lower edges of the leg-like downwardly projecting portions of the head plates, and have bearing openings 27 at their lower ends to receive pintles 28 at opposite ends of a cross bar 29 for pivotally supporting said bar. Openings 30 are provided in the bar to admit the upper ends of the hanger rods 16 which are screw-threaded to receive nuts 31 whereby the rods are supported from the bar and anchor nuts 32 25 overlying the opposite face of the bar. The outer ends of the pintles are reduced and threaded to receive washers 33 and nuts 34.

20 The arms are held in spaced relation for parallel suspension from the pins 25 by a 30 reinforcing and stiffening plate 35 bolted to lateral brackets or lugs 36 on the inner faces of the arm.

35 In ordinary practice, the pivotal mounting point of the polish rod moves horizontally about $2\frac{3}{8}$ inches during the rocking movement of a beam having a lever arm of about 12 feet in length from the post trunnion to the rod pivot, and the rod is bent correspondingly. The distance named represents the maximum spacing of the center 40 of the arc over which the point moves from the chord of the arc. I reduce said spacing, by the structure described, and by further elements now to be described.

45 I locate the upper hinge pins in such relation with the trunnion 7 and the well that when the beam is horizontal the hanger arms will depend substantially perpendicularly and parallel with the axis of the well, and 50 in a plane spaced or offset as presently described from the axis of the well on the side of the Samson post.

55 A stop member 37 is then further provided at the lower edge of the head wings in such a position that when the end of the beam moves upwardly from horizontal position into the upper half of its arc the stop will engage the arms and restrain the same from pivoting, so that the arms will be 60 tipped and the rod supporting cross bar mounted in the lower ends of the arms will pivot. The arms contact the stop when the beam operates above center, and swing free to the outside when the beam operates below center.

The stop comprises preferably a bar 38 mounted in the lower end of the wings and having ends protruding laterally therefrom to engage the swinging arms.

70 Reinforcing plates 39 are preferably riveted to the depending wings of the head plates and flanged bases 40 are provided for attaching the trunnions 25 to the housing, the plates 39 and bases 40 on each head plate being in edge abutment, and the pins of the bar 38 extending through the lower edge portions of the reinforcing plates. Channels 41 may be mounted on the beam for 75 spacing the head plates and supporting the head, end flanges 43 of brackets 44 fixed to the channels being riveted to the plates.

80 The suspending device therefore provides two hinges, the upper hinge coming into action when the beam is moving below a horizontal plane including said hinge, and being prevented from functioning when the beam is moving above said plane, whereupon the lower hinge becomes effective.

85 The path of the rod pivot is therefore divided, because of the provision of the two pivot points, the arcs in which the two pivots move being equal, and substantially less than the arc of the pivot in ordinary structure of this character.

90 The location of the upper pivot or hinge in an example of the use of the invention wherein the radius of the arc or distance of the upper hinge from the beam trunnion is 12 feet, would be at such a point that when the arms 19 hang vertically they are in a 100 plane offset $\frac{5}{8}$ inch from the center of the well on the side of the same toward the Samson post.

95 In the example mentioned, the distances are proportionate to a stroke of 27 inches. 105 The walking beam is adapted to be in horizontal position when the crank is horizontal, and the length of the pitman is adjusted to meet this condition in order to provide minimum lateral movement of the polish rod.

110 What I claim and desire to secure by Letters Patent is:

1. In combination with a walking beam, a rigid head suspended from said beam, a jointed hanger unit including an upper section pivotally mounted on said head and a lower section adapted for coupling to a polish rod, and a stop on the head spaced from the beam and engageable by said upper section to limit inward movement of said section during upward travel of the beam.

115 2. In combination with a walking beam, a rigid head plate on said beam, a hanger arm pivotally suspended from said plate, a hanger bar pivotally suspended from said arm, means on the arm for coupling to a polish rod, and a stop on said plate engageable by said arm beneath the arm mounting for limiting inward movement of the arm on upward travel of the beam.

3. In combination with a walking beam, head plates fixed to and suspended from the beam, arms pivotally mounted on and suspended below the plates, a cross bar pivotally mounted on said arms, rods suspended from the cross bar, means on the lower ends of the rods for supporting a polish rod, and stops fixed to the head plates engageable by the arms to limit inward pivotal movement
5 of the arms on upward travel of the beam.

4. In combination with a walking beam, head plates fixed to and suspended from the outer end of the beam, studs on said plates, arms pivotally suspended from said studs, 15 a cross bar having end bearing members pivotally mounted in the lower ends of said arms, rods suspended from said cross bar, means on the lower ends of the rods for connection with a polish rod, and stop members 20 projecting from said plates and engageable by the rear edges of said arms to limit rearward swinging movement of the arms upon upward movement of the beam.

5. In a device of the character described 25 including a pivotal walking beam, a head plate fixed to the beam, and a hinged hanger unit including an upper section pivoted to said plate and a lower section adapted to support a polish rod, a stop member on said 30 plate engageable by said upper section to limit horizontal movement of said section on pivotal movement of the beam.

6. In a device of the character described including a pivotal walking beam, hanger 35 arms, and a rod-supporting bar pivotally mounted in the lower ends of said arms, a head including plates fixed to said beam having means for pivotally supporting said arms, and including wings depending below 40 said beam and provided with stop members engageable by said arms to limit rearward swinging movement of the arms upon upward movement of the beam.

In testimony whereof I affix my signature.
45 LA RUE B. CHEVALIER.
